UNITED STATES PATENT OFFICE.

CHARLES G. LIDMAN, OF LEAD, SOUTH DAKOTA.

ATTACHMENT FOR KEEPING SCREENS IN GOLD-QUARTZ MILLS CLEAN.

SPECIFICATION forming part of Letters Patent No. 782,861, dated February 21, 1905.

Application filed February 11, 1904. Serial No. 193,109.

To all whom it may concern:

Be it known that I, CHARLES G. LIDMAN, a citizen of the United States, residing in the city of Lead, Lawrence county, South Dakota, have invented a new Improvement or Attachment for Keeping Screens in Gold-Quartz Mills Clean, of which the following is a specification.

I attain this object by the mechanism illustrated in the accompanying drawings, in which—

Figure 1 is a vertical section, and Fig. 2 is a front view, of the attachment.

Similar letters refer to similar parts throughout both views.

A is the cam attached to the cam-shaft.

B is a piece of iron or steel bolted to the cam-floor and hinged in the middle, so that the end toward the cam will work up and down.

C is a connecting-rod, connecting the movable end of B to an arm attached to the shaft D, and this shaft is held by two brackets fastened to the lower side of the cam-floor, and to this shaft is fastened the spring E.

F is a connecting-rod that connects another arm on the shaft D with the crank end of the screen-cleaner proper. In the center of this connecting-rod is a hollow piece with a three-

fourth-inch reducer in each end with thread cut therein to screw onto each end of the connecting-rod, so that the stroke of the screen-cleaner may be easily and accurately adjusted.

G is the screen-cleaner.

When the cam in its revolutions strikes the movable part or end of the hinged piece B, it presses it downward, which raises the screen-cleaner G, and when the cam releases B by force of the spring E the movable end of B is raised, which, by means of the arms and connecting-rod F, causes the screen-cleaner to strike against the screen H, and by reason of the stroke the screen is jarred and shaken, thus releasing all choking substances.

What I claim as my invention, and desire to secure by Letters Patent, is—

The combination with a mortar-screen, of a bail having side arms hinged to the mortar-frame and connected to a moving part of the stamp to effect impact between the cross-bar of the bail and the screen, which by means of the combination set forth, operates substantially as set forth.

CHARLES G. LIDMAN.
